[57] CLAIM

The ornamental design for an apparatus for roughening
and cleaning a surface or the like, as shown.

DESCRIPTION

FIG. 1 is a perspective view of the apparatus for roughening and cleaning a surface or the like taken from the top, front and left sides thereof and showing my new design,

FIG. 2 is a perspective view thereof taken from the top, front and right sides thereof, and

FIG. 3 is a rear elevational view thereof.

FIG. 1

FIG. 2

Fig. 3.
